COMPRESSOR

Orley R. Stephenson and Alford H. Stephenson,
Oakland, Calif.; Beth N. Stephenson, sole heir
of said Alford H. Stephenson, deceased, assignor
to said Orley R. Stephenson

Application January 15, 1945, Serial No. 572,761

10 Claims. (Cl. 230—188)

This invention relates to apparatus for compressing air and other gases.

In the past many devices of this character have been manufactured and sold, all of said devices operating with varying degrees of efficiency. In the past, however, such devices have customarily been cumbersome and complicated and much of the power used to operate them has been absorbed in various unnecessary functions.

It is an object of the present invention to provide a compressor making use of the absolute minimum number of parts whereby simplicity of design and construction will be achieved and loss of efficiency due to friction of excess parts eliminated.

It is a further object of this invention to provide a device of the kind described which is compact in its design, light in weight, and which requires the minimum of attention by an operator.

Further objects and advantages of this invention will appear from the following description of the preferred embodiment of the same and illustrated in the accompanying drawing in which:

Figure 1 is a front elevational view of a compressor incorporating our invention.

Figure 2 is a side elevational view of a compressor incorporating our invention.

Figure 3 is a cross sectional view taken along line 3—3 of Figure 2 with a portion of the cylinder head cut away to show the valve construction.

Figure 4 is a cross sectional view taken along line 4—4 of Figure 2.

Figure 5 is a cross sectional detail taken along line 5—5 of Figure 2.

This device consists generally of three principal parts: A stationary assembly element 10 comprising a cylinder, cylinder heads and valve assemblies, and a suitable mounting pedestal; a reciprocating assembly 11 consisting generally of a piston adapted to reciprocate within the cylinder and suitable piston rod; and a rotatable assembly 12 consisting generally of a cam and means for driving the same.

As shown in Figures 1, 2 and 3, stationary assembly 10 consists generally of an open ended cylinder 15 on both ends of which are mounted identical cylinder heads 16 and 16a, which accommodate identical inlet and outlet valve assemblies 17 and 18 respectively (see Figure 5).

The entire apparatus is mounted upon a suitable pedestal 20 which may be suitably secured to any foundation as by means of foot 21. Pedestal

20 is suitably secured to the stationary portion 10 of our device as by means of suitable bolts 22.

Cylinder heads 16 and 16a are suitably mounted upon opposite ends of cylinder 15 and secured thereto as by means of bolts 23 and gaskets 24.

Inlet and outlet valve assemblies 17 and 18 are generally of the type adapted to be operated by differential pressure. As shown in Figure 5, inlet valve assembly 17 is mounted in a suitably drilled and tapped cavity 30 in cylinder heads 16 and 16a respectively. Assembly 17 consists generally of a removable bridge 31 which provides a valve seat 32 and a valve guide 33 and which is adapted to be held in proper position within cavity 30 by means of removable plug 34, threads 35 of which are adapted to cooperate with the tapped portion of cavity 30. Valve 36 is adapted for longitudinal movement within valve guide 33 and is adapted to cooperate with valve seat 32. Valve 36 is normally held in closed position with respect to valve seat 32 as by means of suitable spring 37 operating against the lower side of flange 38 upon the upper end of the valve stem 39.

Valve assembly 18 is adapted to be mounted in a suitably drilled and tapped cavity 50 in cylinder heads 16 and 16a respectively, and consists generally of a removable plug 51 forming a valve guide 52 within which valve 53 is mounted for longitudinal movement. Valve 53 is adapted to cooperate with valve seat 54 and is urged to closed position in contact therewith by virtue of spring 55. Plug 51 is provided with threads 56 which are adapted to cooperate with the tapped portion 57 of cavity 50 of cylinder head 16 and 16a. Both cap 58 of inlet valve assembly 17 and cap 51 of exhaust valve assembly 18 are provided with suitably tapped orifices 59 and 59 respectively. Threaded orifices 58 are adapted to accommodate so-called conventional "unloaders" (not shown) which are responsive to the pressure in the pressure tank whereby when the pressure within that tank exceeds a predetermined value, the "unloader" will operate to restrain the closing of inlet valves 36, whereby further compression is prohibited.

From the foregoing it is obvious that when the pressure within cylinder heads 16 and 16a respectively is less than the pressure on the "atmosphere" side of inlet valve 36, that inlet valve 36 will open and allow the introduction of air or other gas into the cylinder heads 16 or 16a. It

is also obvious that a decrease in pressure within cylinder heads 16 or 16a will close valve 53.

When the pressure within cylinder heads 16 or 16a exceeds the pressure on the outlet side of valve 53, that valve 53 will be open whereby air or other gas compressed within cylinder heads 16 or 16a will be forced through cavity 58 into a suitable storage tank (not shown). It is obvious that an increase in pressure within cylinder heads 16 and 16a will not open valve 56 but will urge the same to closed position.

The exhaust or outflow ports 60 may be connected by any suitable manifolding to a suitable storage tank, not shown. The inlet passages 61 may open directly to the atmosphere or may be connected to suitable filter means, not shown.

The reciprocating assembly 11 consists generally of a piston 70 provided with suitable piston rod 71 and suitable piston rings 72, and is adapted to reciprocate within cylinder 15. Piston rod 71 reciprocates in suitable bearings 73 mounted in cylinder heads 16 and 16a. Piston rod 71 is suitably machined at its ends substantially as shown in Figure 4 for cooperation with cam 80.

Rotatable assembly 12 consists generally of cam 80, driving element 81 and housing 82 and is rotatably mounted upon shaft 83. A shaft or spindle 83 is suitably secured to stationary assembly 10 as by means of bolts 84, for example. Housing 82 is suitably mounted upon shaft 83 as by means of conventional bearing assemblies 86 and 87, which, as shown, are suitably mounted upon shaft 83 and are adapted to cooperate with the suitable hub 88 of housing 82. The entire assembly is held upon shaft 83 by means of nut 90 and lock nut 91 which cooperate with the threaded portion 82 of shaft 83. Longitudinal movement of housing 82 and its associated parts with respect to shaft 83 (when nuts 90 and 91 in the position shown in Figure 3) is prevented by shoulders 93 and 94 of hub 88 and shoulder 95 on shaft 83 against which shoulders, bearing assemblies 86 and 87 are in contact. Bearings 86 and 87 permit the rotation of assembly 12 about shaft 83 and serve as thrust bearings to prohibit longitudinal movement of assembly 12 with respect to shaft 83 and assembly 10. A suitably threaded cap 98 is adapted to cooperate with the threaded portion 99 on hub 88. A suitable gasket 100 provides a leak proof seal between cap 98 and hub 88.

Housing 82 is suitably secured to pulley 81 and cam 80 by means of suitable bolts 102. Pulley 81 is adapted to be driven by any suitable means of power, by means of a V-belt, not shown, which cooperates therewith. Rotation of pulley 81 causes rotation of the entire rotatable assembly 12 including cam 80 and housing 82.

We have provided an inner annular dished-out member 110 which is suitably secured to cylinder 15 by means of bolts 84. Member 110 is in frictional engagement with the cylinder heads 16 and 16a at points 111 and 111a and 112 and 112a respectively and is provided with orifices 113 and 114 through which piston rod 71 may pass. Orifices 113 and 114 are of slightly greater diameter than piston rod 71 and do not contact the same. The outer annular edge of member 110 is provided with an outwardly extending annular flange 115, which in turn is provided with an inwardly extending annular lip 116.

A cooperating coaxially aligned annular facing ring 118 is suitably secured to rotatable cam 80 as by means of the aforementioned bolt 102 and is provided with an outturned annular lip 119.

Coaxially aligned annular flange 115 and annular facing 118 and concentric lips 116 and 119 cooperate to form a suitable housing for an annular gasket 120 whereby the escape of lubricant or other liquid from the interior of rotatable element 12 is prohibited.

Housing 82 is provided with a suitably threaded orifice 125 adapted to accommodate plug 126 whereby a suitable lubricant may be introduced into the area inside of housing 82, and hub 88, cap 98, member 110 and annular facing ring 118. Lubricants within the above defined area provide lubrication for bearings 86 and 87, piston rod 71 and cam track 80, and connecting rod 71 and bearing 73.

As shown in Figure 4, cam 80 is adapted to cause piston 70 to reciprocate three times within cylinder 15 upon each rotation of rotatable element 12, by the operation of cam surface 80a against the camming surfaces of piston rod 71.

It will be appreciated that the cam track 80a need not be the identical cam track herein disclosed. However we believe that the cam track developed here in which the rate of reciprocation of the piston 70 within the cylinder 15 is the greatest during the middle of its stroke and in which the rate of reciprocation is decreased at the end of the stroke is desirable.

Operation of the device may be briefly described as follows:

Exhaust ports 60 are connected by means of suitable manifolding to a pressure storage tank in any conventional manner, both the manifolding and the storage tank being conventional. Rotatable assembly element 12 is adapted to be driven by any suitable source of power, as for example an electric motor or internal combustion engine as by means of a V-belt cooperating with pulley 81. Rotation of pulley 81 causes similar rotation of the entire rotatable assembly 12 including housing 82 and cam 80. Rotation of cam 80 results in a camming action against the ends of piston rod 71 thereby causing reciprocation of piston 70 within cylinder 15 creates differential pressure therein, thereby operating inlet valves 17 and exhaust valves 18.

For example, movement of piston 70 toward cylinder head 16 compresses the gas in that end of cylinder 15 adjacent cylinder head 16. When the pressure of the gas or air in cylinder head 16 increases beyond the combined pressure of spring 55 and the air pressure in the pressure storage tank, valve 53 opens and the compressed gas within cylinder head 16 is forced therethrough into the manifolding of the exhaust side of valve 53.

The same movement of piston 70 reduces the pressure in cylinder head 16a and tends to create a vacuum therein. When the vacuum pressure within cylinder head 16a overcomes the force exerted upon valve 36 by valve spring 37, valve 36 opens establishing communication between the interior of cylinder head 16a and the atmosphere whereby air at atmospheric pressure is free to enter cylinder head 16a and that portion of cylinder 15 adjacent thereto.

Reciprocation of piston 70 within cylinder 15 in the opposite direction has the opposite effect; to wit, drawing air from the atmosphere through the inlet valve 36 in cylinder head 16 and forcing the compressed air through the exhaust valve 53 in cylinder head 16a, achieving a double action effect.

With the use of the cam track shown in Figure 4, three complete reciprocations of piston 70

Within cylinder 15 are achieved upon each revolution of cam 80, resulting in six pressure and six suction strokes of piston 70.

In the event the use of a belt drive on pulley 81 is undesirable, any suitable means may be used to rotate unit 12. We have shown, for example, a coaxially aligned collar 130 which may be suitably secured to assembly 12 as by means of bolts 131. Collar 130 is provided with an annular flange 132 by means of which it may be connected to any suitable source of power thereby providing means whereby assembly 12 may be rotated resulting in the reciprocation of piston 70 within cylinder 15.

We claim:

1. In a rotary compressor adapted to be driven by a suitable source of power, a stationary assembly comprising a double acting cylinder having a pair of cylinder heads each of which accommodates a suitable valve mechanism, a reciprocating assembly comprising a piston and a piston rod having two external ends projecting from said cylinder heads and adapted to reciprocate with respect to said stationary assembly, and a rotating assembly mounted for rotation with respect to and about said stationary assembly and comprising a cam and adapted to be connected to said source of power whereby said cam may be rotated, both of said external ends of said piston rod adapted to cooperate with said cam whereby rotation of said rotating assembly causes reciprocation of said reciprocating assembly.

2. In a rotary compressor; a stationary assembly comprising a cylinder, a cylinder head and valve assembly at both ends of said cylinder; a reciprocating assembly comprising a piston adapted to reciprocate within said cylinder and a piston rod having two external ends connected to said piston, each of said external ends extending through one of said cylinder heads; and a rotating assembly comprising a cam adapted to surround and rotate with respect to said stationary assembly and to contact both said external ends of the piston rod.

3. In a device of the character described; a stationary assembly comprising a cylinder having a pair of opposed cylinder heads, and inlet and exhaust valve assemblies mounted in said cylinder heads; a reciprocating assembly comprising a piston adapted to reciprocate in said cylinder, a piston rod having two external opposed ends which are adapted to pass through the cylinder head at each end of said cylinder; and a cam adapted to rotate about said stationary assembly and adapted to cooperate with said external opposed ends of said piston rod whereby the piston may be reciprocated within said cylinder upon rotation of said cam, reciprocation of said piston within said cylinder creating differential pressures therewithin thereby operating said inlet and said exhaust valves.

4. In a device of the character described, a stationary assembly comprising a cylinder having a cylinder head at each end and each cylinder head having a valve assembly, a reciprocating assembly comprising a piston and a piston rod having a pair of opposed external ends and a rotating assembly comprising a cam adapted to cooperate with the external ends of said piston rod to cause reciprocation of said piston within said cylinder, said rotating assembly being mounted upon a spindle suitably secured to said stationary assembly, and means upon said rotating assembly whereby the same may be suit-

ably secured to an outside source of power and caused to rotate with respect to and about said stationary assembly.

5. In a rotary compressor adapted to be driven by a suitable source of power; a stationary assembly comprising a spindle and a double ended cylinder having a cylinder head at each end, said cylinder heads each adapted to accommodate a valve mechanism; a reciprocating assembly comprising a piston and a pair of piston rods extending in opposite directions from said piston and adapted to reciprocate with respect to said stationary assembly; and a rotating assembly comprising a cam and being mounted upon said spindle and being adapted to rotate with respect to said stationary assembly about said spindle, both external ends of said piston rods being adapted to cooperate with said cam whereby rotation of said rotating assembly causes reciprocation of said piston.

6. In a rotary compressor, a stationary assembly comprising a cylinder, a pair of cylinder heads mounted on opposite ends of said cylinder, and a projecting stationary spindle; a reciprocating assembly comprising a piston adapted to reciprocate within said cylinder and a pair of piston rods connected to said piston and extending from opposite faces of said piston through both of said cylinder heads; and a rotating assembly mounted upon said spindle and adapted to rotate with respect to said spindle and said stationary assembly, said rotating assembly comprising a cam adapted to cooperate with the ends of said piston rods extending through said cylinder heads and to cause the same to reciprocate with respect to said stationary assembly upon rotation of said rotating assembly.

7. In a device of the character described; a stationary assembly comprising a cylinder, two cylinder heads, an inlet and outlet valve assembly in each of said cylinder heads, said valves being operated by differential pressure; a reciprocating assembly comprising a piston adapted to reciprocate in said cylinder and a piston rod having two external ends adapted to pass through said cylinder heads; a rotating cam surrounding the stationary assembly and adapted to cooperate with the external ends of said piston rod whereby the piston may be reciprocated within said cylinder upon rotation of said cam, reciprocation of said piston within said cylinder creating differential pressure therewithin thereby operating said inlet and said exhaust valves.

8. In a device of the character described adapted to be driven by an outside source of power, a stationary assembly comprising a cylinder having a cylinder head at each end, each of said cylinder heads having inlet and exhaust valve assemblies, the inlet valves opening to the atmosphere and the outlet valves being connected to a suitable storage tank, said valves being operated by differential pressure within said cylinder; a rotatable cam, a reciprocating piston adapted to reciprocate in said cylinder, a pair of coaxially aligned piston rods extending from opposite faces of said piston through said cylinder heads and adapted to operate said piston, the external ends of said rods cooperating with said rotating cam which surrounds said stationary assembly and which is adapted to be driven by said outside source of power, and reciprocation of said piston creating differential pressures within said cylinder thereby operating said inlet and exhaust valves.

9. In a device of the character described, a stationary assembly comprising a double acting

cylinder having two cylinder heads and valve assemblies in said cylinder heads, said valve assemblies comprising inlet and exhaust valves being operated by differential pressures within said cylinder, a reciprocating assembly comprising a piston adapted to reciprocate within said cylinder and a pair of piston rods connected to opposite faces of said piston and extending through both of said cylinder heads; a rotating assembly comprising a cam adapted to surround and rotate with respect to said stationary assembly and to engage the ends of said piston rods extending through said cylinder heads whereby when said cam is rotated said piston is caused to reciprocate within said cylinder and create differential pressures therein whereby reciprocation of said piston in one direction opens the exhaust valve in one of said cylinder heads and the inlet valve in the other of said cylinder heads and reverse reciprocation of said piston within said cylinder opens the inlet valve in said first cylinder head and the exhaust valve in said second cylinder head.

10. In a device of the character described, a stationary assembly comprising a cylinder having a pair of cylinder heads including therein suit-

able valve assemblies, a piston and a piston rod having two external ends in which each of said external ends of said piston rods is adapted to extend through one of said cylinder heads on the ends of said cylinders, and a rotating cam adapted to rotate about said stationary assembly and to contact both said external ends of the piston rod.
